CLAIM

The ornamental design for a hand held bible computer, as shown and described.

DESCRIPTION

FIG. 1 is a perspective view of a hand held bible computer in the opened position showing my new design, the pencil being shown in broken lines for illustrative purposes only and forms no part of the claimed design; FIG. 2 is an end elevational view thereof in the closed position;

FIG. 3 is an opposite end elevational view thereof;

FIG. 4 is a side elevational view thereof;

FIG. 5 is an opposite side elevational view thereof;

FIG. 6 is a bottom plan view thereof;

FIG. 7 is a top plan view thereof;

FIG. 8 is an end elevational view thereof in the opened position;

FIG. 9 is an opposite end elevational view thereof;

FIG. 10 is a perspective view of a second embodiment of my design in the opened position, the pencil being shown in broken lines for illustrative purposes only and forms no part of the claimed design;

FIG. 11 is a perspective view thereof in the closed position;

FIG. 12 is a perspective view of a third embodiment of my design in the opened position, the pencil being shown in broken lines for illustrative purposes only and forms no part of the claimed design;

FIG. 13 is a perspective view thereof in the closed position.

The undisclosed views of the second and third embodiments are identical to those of the first.
